UNITED STATES PATENT OFFICE

ERNST BECKER, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

INTERNAL-COMBUSTION ENGINE

Application filed April 17, 1928, Serial No. 270,694, and in Germany April 27, 1927.

My invention relates to improvements in internal combustion engines.

It is already known to construct crank-shafts in such a manner that the crank-pin 5 may be detached from the crank-arm, for the purpose of allowing bearing rings or ball-races and the like to be placed in position upon the pin. Joints of this kind are generally constructed in such a way that the 10 end of the crank-pin is tapered and forced or drawn into a correspondingly tapering bore of the crank-arm by means of a screw. There are also known arrangements in which the crank-arm is provided with a split recess 15 or bore, which is provided with a large number of key-like projections uniformly spaced around the entire circumference. These projections engage correspondingly shaped grooves or keyways in the crank-pin and prevent 20 the pin from rotation, while the attachment of the pin is effected by clamping the split crank-arm. In this latter arrangement a good fit at the sides of the keys is attained at those fitting keys only, which are disposed 25 at the curvature located diametrically opposite the slit.

According to my invention the crank-arm is provided with a recess or bore, which shows only two fitting key-like projections 30 arranged symmetrically to the axis and at an angle of 120° apart.

An embodiment of my invention is illustrated by way of example in the drawings affixed hereto and forming part of my invention.

In these drawings:

Fig. 1, represents an internal combustion engine in sectional elevation, to which my invention is applied,

Fig. 2, the improved crank-arm in front-elevation, and in larger scale,

Fig. 3, the crank-arm of Fig. 2 in partly sectional side elevation, and

Fig. 4, the pertaining crank-pin together 45 with its other crank-arm in side elevation.

Referring to the drawings it will be seen that the crank-shaft 9 is journaled at the points 13 in the engine casing. The connecting rod 12 engages the crank-pin 6 which is 50 located between the two crank-arms 1 and 11.

The crank-arm 1 contains a boring 2 provided with an axially extending slit 3. At the semicircle, opposite this slit, the boring is provided with two projections 4 acting as keys and which are spaced apart by 120° and are located symmetrically to the axis. This arrangement has the advantage that the keys 4 are thus located at that part of the curvature of the boring, which is least interfered with by the deformation which occurs when the ends of the split crank-arm are drawn together. The end of the crank-pin 6 entering the bore of the crank-arm is provided with grooves 5 fitting the keys 4, and which may be produced in the usual manner by 55 planing or milling. During the assembly the crank-pin 6 is introduced into the boring 2 of the crank-arm 1 and the ends of the arm are then drawn together by a bolt threaded into the tapped bore 8. By this clamping 60 process the upper portions of the crank-arm are firmly pressed against the pin. 65

In this way a joint between the crank-pin and the crank-arm is obtained which closely fits all along the circumference and which combines great durability with ease and cheapness of production. It has the further advantage that it is easily detachable and yet offers absolute security against the turning of the pin within the crank. It is not absolutely necessary, that the crank-pin should be detachably joined to both crank-arms, it may equally well be integral with one arm of the crank or be attached to it in any other suitable manner. 70

In producing the boring 2 the crank-arm 1 is according to the invention first provided with a bore of smaller diameter corresponding with the thickness of the projections 4. The material between the projections is then cut away in any suitable manner, preferably with a broach. Since, however, a broaching pin with only two recesses at 120° apart would not ensure a uniform guidance, a broach is preferably employed the profile of which shows recesses for three projections spaced by 120° . The third of the projections 7 thus obtained is shown in broken lines in Fig. 1. Since the remainder of this projection after the milling of the slot would not ensure 75

a reliable fit owing to the deformation when the arm end is clamped together, this remainder is cut away after the completion of the broaching operation.

6 Various modifications and changes may be made without departing from the spirit and the scope of the invention, and I desire, therefore, that only such limitations shall be placed thereon as are imposed by the prior art.

10 I claim as my invention:

1. A divided crank-shaft having at least at one end of its crank-pin a detachable connection with the pertaining crank-arm, said connection comprising a boss at said pin end, said crank-arm having a boring adapted to receive said boss and being split open at one point of said boring in axial direction thereof, and two axially directed key way connections between said boss and said crank-arm boring, spaced substantially 120° apart, and being symmetrically disposed opposite the split portion of said crank-arm, and means for clamping the split arm portion together.

2. A divided crank-shaft having at least at one end of its crank-pin a detachable connection with the pertaining crank-arm, said connection comprising a boss at said pin end, said crank-arm having a boring adapted to receive said boss and being split open at one point of said boring in axial direction thereof, said boring having two axially directed keys protruding from its periphery and being integral with the crank-arm, said keys being spaced apart substantially 120° and being symmetrically disposed opposite the split portion of the crank-arm, said boss having two corresponding key ways adapted to engage said keys, and means for clamping the split arm portion together.

3. A divided crank-shaft having at least at one end of its crank-pin a detachable connection with the pertaining crank-arm, said connection comprising a boss at said pin end, said crank-arm having a boring adapted to receive said boss and being split at its end in axial direction of said boring, and two axially directed key way connections between said boss and said crank-arm boring, spaced substantially 120° apart, and being symmetrically disposed opposite the split portion of said crank-arm, and means for clamping the split arm portion together.

4. A divided crank-shaft having at least at one end of its crank-pin a detachable connection with the pertaining crank-arm, said connection comprising a boss at said pin end, said crank-arm having a boring adapted to receive said boss and being split at its end in axial direction of said boring, said boring having two axially directed keys protruding from its periphery and being integral with the crank-arm, said keys being spaced apart substantially 120° and being symmetrically disposed opposite the split portion of the crank-arm, said boss having two correspond-

ing key ways adapted to engage said keys, and means for clamping the split arm portion together.

In testimony whereof I affix my signature.

ERNST BECKER.
